US0D1043645S

(12) **United States Design Patent** (10) **Patent No.:** **US D1,043,645 S**
(45) **Date of Patent:** **** Sep. 24, 2024**

(54) **CASE FOR MOBILE TELEPHONE**

(71) Applicant: **Foshan Shuntenghui Technology Co., Ltd.**, Foshan (CN)

(72) Inventor: **Shengen Zhang**, Meizhou (CN)

(73) Assignee: **Foshan Shuntenghui Technology Co., Ltd.**, Foshan (CN)

(**) Term: **15 Years**

(21) Appl. No.: **29/882,020**

(22) Filed: **Jan. 10, 2023**

(51) LOC (14) Cl. **03-01**

(52) U.S. Cl.

USPC **D14/250**

(57) **CLAIM**

The ornamental design for a case for mobile telephone, as shown and described.

DESCRIPTION

FIG. 1 is a first perspective view of a case for mobile telephone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the case for mobile telephone thereof; and,

FIG. 10 is an enlarged view of the selected portion 10 in FIG. 1.

The broken lines shown in the drawings depict portions of the case for mobile telephone that form no part of the claimed design.

1 Claim, 10 Drawing Sheets
